APPARATUS FOR FLAME MACHINING

Herbert E. Serner, Oakland, N. J., assignor, by
mesne assignments, to Union Carbide and Car-
bon Corporation, a corporation of New York

Original application May 7, 1935, Serial No.
20,167. Divided and this application February
24, 1938, Serial No. 192,355

11 Claims. (Cl. 266—23)

This invention relates to an improved apparatus for flame machining wherein heated metal is removed from the surface of a metallic body by progressively applying a plurality of oxidizing gas streams simultaneously to successive portions of such a surface. More particularly, this invention relates to apparatus for flame machining surfaces of metallic bodies to produce shaped surfaces having a predetermined contour.

10 This application is a division of my Patent No. 2,125,180, issued July 26, 1938, for an improvement in Method of flame machining.

In starting a flame machining operation to remove metal, a portion of the surface is heated sufficiently to produce a wet surface film of molten metal. When an oxidizing gas stream is applied to such wet film, it tends to spread over an area of surface metal that is subjected to the influence of the oxidizing gas stream.

15 This wet film or puddle, which comprises a mixture of molten metal and oxidized metal, is believed to be essential to enable the oxidizing gas stream to penetrate into the metal to melt and oxidize the same. The heat of reaction resulting from the oxidation of molten metal heats metal ahead of the oxidizing gas stream so that, when the gas stream is progressively applied along the surface, a wet surface film is always produced at the areas acted upon by the gas stream.

20 Although I do not wish to be held to the exact theory of flame machining just described, constant observation and study of flame machining operations does indicate that the wet surface film produced is essential to maintain a cut and remove metal continuously from successive portions of a surface.

In accordance with my invention, surfaces having a predetermined contour are produced by flame machining by controlling the shape of the wet surface film and the manner in which it is formed at successive surface portions from which metal is to be removed. In the present application of my invention a plurality of oxidizing gas streams are utilized to control and maintain a single wet surface film or puddle, with one of the streams applied to a surface at the rear of a preceding gas stream to produce the desired cut in a single pass of the gas streams relatively to the metallic surface. By this method surfaces having a predetermined contour can be produced which are exceptionally smooth with no rough portions to define the separate action of the individual oxidizing gas streams.

The objects of this invention, therefore, are:

55 to provide an improved apparatus for flame ma-

ching whereby surface metal can be removed from an edge surface of a metal body in such a manner that any predetermined surface contour thereon can be produced; and to provide an improved apparatus for holding and guiding a nozzle having two or more discharge orifices for producing a plurality of oxidizing gas streams which, when applied on a metallic surface, effectively coact to produce a relatively smooth cut effectively removing metal to produce a surface

10 having a predetermined contour.

Further objects and advantages of my invention will become apparent as the following description proceeds, and the features of novelty which characterize my invention will be pointed out in the claims annexed to and forming a part of this specification.

In the drawings Fig. 1 diagrammatically illustrates one manner of applying two oxidizing gas streams at the edge of a metallic body to coact and produce a smooth cut; Fig. 2 is a view taken at line 2—2 of Fig. 1 to illustrate more clearly the contour of the surface produced; Fig. 3 is a view similar to Fig. 1 and diagrammatically illustrates the action of two oxidizing streams which coact to produce a cut having a contour different from that produced in Fig. 1; Fig. 4 is a view taken at line 4—4 of Fig. 3 to show more clearly the type of cut produced; Fig. 5 is a perspective view of the metallic body shown in Fig. 1 to illustrate more clearly the manner in which the metal is removed to produce the cut; Fig. 6 is a sectional view of a nozzle for use with the apparatus of this invention taken at line 6—6 of Fig. 7; Fig. 7 is an end view of the nozzle taken at line 7—7 of Fig. 6; Fig. 8 is a sectional view of the nozzle taken at line 8—8 of Fig. 7; Fig. 9 is a side view, in elevation, of apparatus embodying my invention in which the nozzle shown in Figs. 6 and 7 is employed to produce cuts of the type illustrated in Fig. 2; Fig. 10 is a plan view of the apparatus shown in Fig. 9; Fig. 11 is a sectional view taken at line 11—11 of Fig. 9; Fig. 12 is an end view of the apparatus in Figs. 9 and 10, taken from the nozzle end; Fig. 13 is a sectional view taken at line 13—13 of Fig. 12.

The method of removing surface metal by employing a plurality of coacting relatively low velocity, oxidizing gas streams is more fully explained in and is claimed in the patent previously referred to.

In flame machining it has generally been the practice to employ a nozzle having a single circular or an elongated discharge orifice for deliv-

55

ering an oxidizing gas stream, and the present method of flame machining can be effectively carried out by utilizing a plurality of such nozzles. By varying the shape of one or more of the discharge orifices of the nozzles employed, changes in the contour of a cut can readily be produced. In place of several independent nozzles it may be preferable in some instances to employ a single nozzle having a plurality of discharge orifices capable of delivering oxidizing gas streams which will coat to produce a smooth cut of a desired contour.

In Figs. 1 and 2 I have diagrammatically illustrated one manner of practicing the method of flame machining to produce a smooth surface having a predetermined contour. The surface contour shown at the edge of plate 10 in Fig. 2 is particularly desirable for electrically welding two of such plates. It will be noted that the portion 11 of the edge surface has a sharp radius of curvature and that the portion 12 extends downward therefrom in substantially a straight line which is at an angle to the original edge or uncut portion 13. When two plates having such an edge surface contour are arranged edge to edge, a U-shaped groove is formed which will permit a welding electrode to extend therein with its fusing end adjacent the very bottom of the groove. This will insure an arc being established between the bottom of the groove and the end of the electrode rather than between the side walls of the groove and the electrode; and when the former occurs a sound and firm weld deposit is obtained.

To make a cut which will produce the surface indicated at 11 and 12 in Fig. 2, a plurality of oxidizing gas streams are employed. As diagrammatically shown, two oxidizing gas streams *a* and *b* may be discharged against the edge surface from the orifices 14 and 15 of a nozzle 16 on a zone spaced a substantial distance below the top surface of the plate 10. In this particular application of my invention, the nozzle 16 is positioned at a slight acute angle to the edge 13 and in such a direction that the metal removed is blown ahead of and sideways of the cut as it is being made.

The oxidizing gas stream *b* is so applied that it effects the first removal of metal from the edge of the plate 10. As shown in Fig. 1, the gas stream *b* strikes the surface about a third of the distance from the top surface of the plate 10. Assuming the surface metal to be sufficiently heated to have a wet surface film formed thereon, melting and oxidization immediately take place, and surface metal in the form of slag is blown ahead of and sideways of the cut, along the surface, by the force of the oxidizing gas stream.

The oxidizing gas stream *a* is applied on the surface of the plate 10 adjacent the uncut portion 13 thereof. The gas stream *a* is arranged to strike the edge at a greater acute angle than the gas stream *b*, so that it will effect the last removal of metal as successive surface portions of metal are removed in the direction indicated by the arrow *c*. Upon striking the edge surface of the plate 10, the gas stream *a* produces the curved portion 11 having a sharp radius of curvature. The gas stream *a* is deflected by the curved portion 11 that it produces, flows under the gas stream *b*, and sweeps across and over the edge surface of the plate 10. In flowing over the lower part of the edge surface of the plate 10, the gas stream *a* tends to merge with the

gas stream *b* and cooperates therewith to remove additional surface metal from the lower portions of the edge surface. In order that the portion 12 of the cut will be substantially straight, as shown, the velocity of the gas stream *a* is sufficient to sweep across and over the entire surface of the finished cut that is produced.

The action of the oxidizing gas streams *a* and *b* during a metal removing operation is clearly shown in Fig. 5. As the cut is progressively being made, the gas stream *b* effects the initial removal of metal from a surface portion *d* extending between the dotted line indicated at 18 and the point 19. Directly behind the gas stream *b* the gas stream *a* effects the removal of a surface portion *e* extending between the point 20 and the dotted line 18. Thus the gas stream *a* effects a complete removal of surface metal over the entire edge to provide a cut which is exceptionally smooth with no rough portions to define the separate action of the streams *a* and *b*. A cut having a sectional surface contour as shown in Fig. 2 may be produced when the orifice 14 that discharges the gas stream *a* is rectangular in shape and the orifice 15 that discharges the gas stream *b* is substantially circular in shape.

As mentioned above, the shape of the surface contour produced can be varied by employing gas streams that are discharged from different shaped orifices of a nozzle or nozzles. In order to produce the cut shown at the edge surface of plate 10' in Fig. 4, for example, two gas streams *f* and *g* may be employed which are discharged from circular orifices 22 and 23 of a nozzle 24. The action of the gas streams *f* and *g* are the same as gas streams *a* and *b*, described above, and hence will not be repeated here. It will be noted, however, that even though the gas streams merge and coat to produce a smooth cut having a double curvature, the velocity of the rear gas stream *f* that effects the final removal of metal is such that the desired projection 25 at the bottom of the cut 26 is produced.

I have found it preferable to preheat successive portions of surface metal to an elevated temperature by high temperature heating flames prior to the application of the oxidizing gas streams. This may be effectively accomplished by providing each nozzle with a plurality of orifices to provide high temperature heating flames. As shown in Figs. 2 and 4, for example, the nozzles 16 and 24 are provided with a plurality of orifices 27 and 28, respectively, for discharging a suitable combustible gas to provide the heating flames.

Although several independent nozzles may be employed to provide a plurality of oxidizing gas streams, it is particularly desirable in many instances to make cuts with a single nozzle having a plurality of discharge orifices. A form of nozzle which is particularly suitable to produce cuts of the type illustrated in Fig. 2 is shown in Figs. 6, 7 and 8. Such a nozzle is fully described and claimed in my copending application Serial No. 191,423, filed February 19, 1938.

Referring to Fig. 6, the nozzle *N* embodying the principles of this invention may have a shoulder 30 at its inner end. An externally threaded clamping nut 31 disposed about the nozzle and bearing against the shoulder 30 is provided for securing the nozzle to a blowpipe head or adaptor, so that the tapered seating surfaces 32 and 33 will engage and form a gas-tight seal with similar seating surfaces in the blowpipe head, which supplies the oxidizing gas.

such as oxygen or a mixture of oxygen and air, and a combustible gas, such as a mixture of oxygen and acetylene, to the nozzle.

Disposed within the outer wall of the nozzle 5 is a group of passages 34 which are substantially equally spaced and which extend longitudinally thereof from an inlet 35 to the discharge face 36. The combustible gas is delivered from the blowpipe head and through the passages 34, which 10 passages are reduced in cross-sectional area at the outer or discharge end of the nozzle. An oxidizing gas passage 37, having an inlet 38 communicating with an outlet in the blowpipe head, extends longitudinally through the nozzle and 15 terminates a short distance from the extreme end of the nozzle. From the outer end or outlet of the passage 37 two separate gas passages 39 and 40 extend to the discharge face 36 of the nozzle. 20 The oxidizing gas passing through the passage 37 is therefore diverted into the passages 39 and 40 to provide two oxidizing gas streams. Where more than two oxidizing gas streams are deemed necessary, the nozzle may be provided with a 25 greater number of passages at the discharge end to provide the number of oxidizing gas streams desired.

The directions in which the oxidizing gas streams are discharged and applied on a metallic 30 surface will depend upon the particular surface contour desired. In the present embodiment, in order to produce the surface contour shown in Fig. 2, the circular gas passage 40 is inclined to the passage 37 in a direction away from the rectangular-shaped passage 39, as shown in the 35 vertical sectional view in Fig. 6. The rectangular-shaped passage 39 is also inclined to the concentric passage 37 in a plane transverse to or at right angles to the vertical plane shown in Fig. 6, 40 and its outlet is offset laterally from that of the passage 40, as indicated in Fig. 8.

When the nozzle N is arranged at an acute angle to the surface of a metallic body from which metal is to be removed, the inclination of the gas 45 passage 39 is toward the surface. With this construction the oxidizing gas stream discharged from the passage 39 will strike the surface at a point closer to the discharge face 36 of the nozzle than the gas stream discharged from the passage 40. To permit the gas stream discharged from rectangular-shaped passage 39 to contact or strike the surface at the shortest possible distance ahead of the nozzle, the passage 39 is so formed that the side walls thereof converge, as indicated 50 in Fig. 8. This produces a gas stream which flares sideways immediately after being discharged from the passage 39, so that it is effectively utilized to produce the portion 11 of cut shown in Fig. 2, which portion preferably should 55 have a sharp radius of curvature to obtain the surface contour desired in this particular instance. In order that the nozzle can be positioned with its tip as close as possible to the surface of a metallic body, the discharge end thereof 60 is tapered, as indicated at 41. This permits the nozzle to be positioned a minimum distance from the metallic body and at the same time insures sufficient clearance as the nozzle is moved relatively to the surface.

70 In Figs. 9 to 13, inclusive, I have shown apparatus embodying the principles of my invention in which the nozzle shown in Figs. 6, 7, and 8 can be effectively employed to produce the surface contour illustrated in Fig. 2.

To move the nozzle N relatively to the edge sur-

face of the plate 10 a self-propelled carriage (not shown) may be used. Such a carriage may be driven on the top surface of the plate 10 and guided by a rail mounted thereon. The carriage may have an arm secured thereto which extends beyond the edge of the plate, and on this arm may be mounted a downwardly extending bracket 50, as shown in Fig. 9. Apparatus of this character is described and claimed in J. H. Bucknam and A. J. Miller application, Serial No. 1,470, filed January 12, 1935. Pivotedly connected to the bracket 50 at 51 is an angle member 52 to which in turn is pivotally secured at 53 a sleeve 54 that partially supports the apparatus, as will hereinafter be described. Since the pivotal connection at 51 permits angular adjustment in a vertical plane and the pivotal connection at 53 permits angular adjustment in a plane perpendicular to the vertical plane, the sleeve 54 can be adjusted in any desired position. To enable an operator quickly to position the sleeve 54 indicating scales 55 and 56 are provided at the pivotal connections 51 and 53, respectively.

In this apparatus the position of the sleeve 54 determines the exact angle at which the oxidizing 20 gas streams discharged from the nozzle N are applied on the edge surface of the plate 10. It is desirable to maintain the nozzle N in its adjusted position during an entire metal removing operation and at the same time permit movement of 25 the nozzle when irregularities in the edge surface are encountered. By permitting such movement of the nozzle, the tip thereof will always remain at the desired position to produce a uniform cut. This is accomplished by providing a flexible connection, such as the parallel linkage mechanism 30 M, for partially supporting the nozzle N on a head 57 which is mounted on the sleeve 54.

To the outer end of the head 57 is threadedly secured an adaptor connection 58 to which is 40 fixedly connected a bracket 59. The parallel linkage mechanism M comprises the fixed bracket 59, a movable bracket 60 to which the nozzle N is detachably secured, short links 61 pivotally connected at one end to the brackets 59 and 60, and links 62 pivotally connected to the free ends of the short links 61. The pivotal connection of the short links 61 to the brackets 59 and 60 permits horizontal movement of the end bracket 60 and nozzle N secured thereto, and the pivotal connection of the links 62 to the short links 61 permits movement of the bracket 60 and nozzle N in a plane transverse to or at right angles to the horizontal movement. The three parallel links 62 are thus universally pivoted at separate points to the supporting bracket 59 and to the nozzle holding bracket 60 and will therefore maintain the brackets substantially parallel to each other. With this arrangement the nozzle N will have vertical and horizontal movement and at the 50 same time its angular position with respect to the plate 10 will always remain constant, this position being determined by the setting of the sleeve 54 on the bracket 50. Oxidizing and combustible gas are delivered from the head 57 and adaptor connection 58 through flexible tubing 63 and 64, respectively, to the oxidizing and combustible gas passages 37 and 34 respectively in the nozzle N.

The nozzle N is also partially supported and guided along the edge of the plate 10 by a roller or guide 65 having its tread L-shaped with the vertical or flange portion 66 bearing against the edge of the plate and the horizontal portion 67 bearing on the top surface of the plate. At the 70

5 juncture of the vertical and horizontal portions of the tread surface of the roller a recess is provided to maintain the tread surface spaced from the extreme edge of the plate, thereby insuring an accurate guiding of the nozzle N even when small projections occur at the extreme edge of the plate. The flange portion of the roller 65 is inclined from the vertical plane in a direction toward the edge of the plate 10 by inclining the 10 axis of the roller at a relatively small angle to the plate surface, the tread surfaces 66 and 67 being frusto-conical. With this arrangement the roller naturally tends to bear against the edge of the plate as it moves relatively thereto, so as to 15 maintain the tip of the nozzle N a constant distance from the edge surface.

15 The roller 65 is journaled at 68 to the lower end of a vertical bracket 69 having at its upper end a sleeve 70 which is mounted on one arm 20 of an angle member 71 and secured thereto by a set screw 72. This arrangement permits angular and axial adjustment of the bracket 69 on one arm of the angle member 71. The other arm of the angle member 71 extends through an opening 25 in a block 73 and is keyed thereto at 74, as shown in Fig. 12, to permit only axial movement thereof. The angle member 71 is maintained in its adjusted position by a set-screw 75.

25 The block 73 is loosely mounted on a shaft 76 30 and is secured thereto through resilient means comprising a torsion spring 77 disposed about a mandrel 78 keyed at 79 to the shaft 76. The mandrel bears against the block 73 and is maintained in position by a set screw 80. The outer 35 end of the spring 77 is secured at 81 to the outer end of the mandrel 78, as shown in Fig. 10, and the inner end thereof is adapted to fit into any one of a plurality of openings formed in the side face of the block 73. The tension of the spring 40 77 can be readily fixed by changing the position of the inner end thereof, and such end can be secured to the block 73 by a set screw 82 adapted to fit into any one of a plurality of openings 45 83 formed on the peripheral surface of the block 73, which openings communicate with the openings formed in the side face of the block 73.

50 A clamping block 84 is also loosely mounted on the shaft 76. The front portion of this block is bifurcated and provided with an opening to receive a threaded stud 85 to attach the block 84 to the top edge of the bracket 60, as shown in Fig. 10. Angular movement of the block 84 with respect to the bracket 60 is prevented by a set screw 86 which extends through threaded openings 55 in the bifurcated arms of the block 84.

55 A screw 87 for adjusting the elevation of the nozzle N extends through an opening in a projection 88 of the block 84, and the end thereof bears against an off-set peripheral portion of a 60 cam 89 fixedly secured to the shaft 76, as shown in Fig. 13. Upon moving the adjusting screw 87 no angular movement can be imparted to the block 84 and bracket 60 to which the nozzle N is secured because, as mentioned above, the angular 65 position of the nozzle N with respect to the plate 10 is dependent solely upon the position of the sleeve 54. The elevation of the nozzle N can be adjusted, however, through the screw 87.

70 When the screw 87 is moved to the right, referring to Figs. 9, 10 and 13, the cam 89 and shaft 76 are rotated clockwise. This clockwise movement of the shaft 76 increases the angle of the angle member 71 with respect to the surface 75 of the plate 10 and moves the roller 65 to the

left. Since the bracket 69 is in a fixed position, the shaft 76 will be moved upward by the angular movement of the angle member 71 and horizontal movement of the roller 65. With such upward movement the shaft 76 will raise the 5 block 84, movable bracket 60, and the nozzle 30.

Conversely, when the screw 87 is moved to the left, the cam 89 and shaft 76 will rotate counter-clockwise due to the weight of the apparatus. This counter-clockwise movement of the shaft 10 76 decreases the angle of the angle member 71 with respect to the surface of the plate 10 and moves the roller 65 to the right. Since the bracket 59 is in a fixed position, the shaft 76 will be moved downward by the angular movement of 15 the angle member 71 and the horizontal movement of the roller 65. With such downward movement the shaft 76 will lower the block 84, movable bracket 60, and the nozzle N. To limit the counter-clockwise rotation of the shaft 76 20 and hence the lowest elevation of the nozzle N, the block 73 is provided with a projecting element 90, the end of which is disposed in the path of a projection 91 secured to the peripheral surface of the cam 89, as shown in Figs. 12 and 13. 25

In a simpler form of apparatus the block 73 30 may be secured directly to the shaft 76. A resilient connection of the block 73 to the shaft N 65 is preferred, however, so that the nozzle N can be lowered to move relatively to the roller 30 65 transversely of the edge surface, when desired, by merely pushing down upon either one or both of the blocks 73 and 84.

The parallel linkage mechanism M may be biased in any suitable manner to maintain the 35 vertical portion 66 of the tread surface of the roller 65 bearing against the edge of the plate 10. As shown in Figs. 9 and 11, downwardly extending flat members 92 and 93 may be journaled at substantially the opposite ends of the 40 two links 62 in the same horizontal plane. A rod 94 extends freely through an opening in the member 93 and is secured at 95 to the member 92. The linkage mechanism M is urged toward the edge of the plate 10 by a helical spring 96 45 disposed about the rod 94 and having the ends thereof bearing against the member 93 and a nut 97 on a threaded portion of the rod. The tension of the spring 96 can readily be adjusted by moving the nut 97 toward or away from the 50 member 93.

The operation of the apparatus illustrated in the drawings is substantially as follows: It will be assumed that the bracket 69 is positioned on the arm of the angle member 71 so that the tip 55 of the nozzle N is a minimum distance from the edge of the plate 10; that the angle member 71 is axially adjusted in the block 73; that the sleeve 54 is adjusted so that the nozzle N is positioned at the desired angle inclined in the direction of 60 advance of the metal removing operation with respect to the edge of the plate 10; that the nozzle N has been positioned at the desired elevation by turning the adjusting screw 87; and that the apparatus is positioned so that the nozzle N 65 is adjacent one end of the plate 10.

With the above assumed conditions, the nozzle N is lowered so that the tip is opposite the bottom surface of the plate 10. This may readily be accomplished by pushing down on the blocks 70 73 and 84, the resilient connection of the block 73 to the shaft 76 permitting this movement. Combustible gas is then supplied to the nozzle N through the tubing 64 and head 57 from a suitable source of supply. Upon igniting the com- 75

bustible gas the portion of the surface impinged by the flame is heated to an elevated ignition temperature. The nozzle N may then be gradually raised by releasing the pressure on the blocks 73 and 84. During this movement a narrow strip of the edge of the plate is heated sufficiently to have a wet surface film formed thereon.

When the nozzle N is at the initially adjusted position, oxidizing gas is supplied thereto through the tubing 63 and head 51 from a suitable source of supply. After a cut has been started, the carriage (not shown) from which the bracket 50 depends, is propelled relatively to the horizontally disposed plate 10, lengthwise of the edge to be flame machined. The oxidizing gas streams issuing from the orifices 39 and 40 of the nozzle will then melt and oxidize the surface metal, and this oxidized and molten metal will be blown ahead of and sideways of the plate edge in a manner previously described, to produce the desired surface contour.

Since the movable parts of the apparatus including the bracket 60, block 84, angle member 71 and guide 65 are biased toward the edge of the plate 10 by the spring 96, any irregularities in the surface of the edge will cause these movable parts to move horizontally; and this movement will cause the nozzle N to move a corresponding distance as it is moving with respect to the plate. Due to the parallel linkage M, however, which moves automatically in response to changes in the position of said guiding means, the nozzle will always remain in its adjusted position during the entire metal removing operation. Similarly, any irregularities in the top surface of the plate 10 will cause the bracket 69 and other movable parts to move vertically and maintain the nozzle N at its adjusted position so that the uncut portion 13 will be of uniform height along the entire edge of the plate.

In view of the foregoing, it will be apparent that I have provided an improved apparatus for removing metal to produce a surface having a predetermined contour. Although the desired surface contour in most instances can be obtained in a single pass of the oxidizing gas streams, the desired surface contour may be produced by several passes of the oxidizing gas streams relatively to a metallic body.

The present apparatus for flame machining is particularly useful in preparing the edges of relatively thick metal plates for welding. The finished surface, flame machined as described, carries a very thin coating of iron oxides after the loose magnetic oxide has been removed from the surface. The thickness of this iron oxide film is substantially equal to a wave length of light, and beneath such oxide film there is a thin layer of metal containing carbon in an amount greater than that of the original metal before the flame machining operation. In this manner the flame machined surface is so conditioned and improved that subsequent welding of two plates having such surfaces is considerably facilitated, and the resulting welded joint has a strength and uniformity superior to joints heretofore produced in this field of welding.

While I have shown a particular embodiment of a nozzle and apparatus for carrying out my improved method, it will be apparent that modifications may be made, and certain features can be used independently of others without departing from the spirit and scope of my invention as set forth in the claims.

I claim:

1. Apparatus for removing metal from the surface of a body, comprising the combination of means disposed adjacent said surface for applying at least one oxidizing gas stream thereon; supporting means; means for flexibly connecting said oxidizing gas stream applying means to said supporting means for partly supporting said applying means and for permitting movement thereof; means adapted to contact said body and movable relatively thereto for guiding said applying means; means resiliently connecting said guiding means to said gas stream applying means whereby said applying means may be moved relatively to said guiding means transversely of said surface; and means for relatively moving said applying means and said body lengthwise of said surface.

2. Apparatus for removing metal from a substantially vertical surface of a body, comprising the combination of means disposed adjacent said surface for applying at least one oxidizing gas stream thereon; supporting means; means for flexibly connecting said oxidizing gas stream applying means to said supporting means for partly supporting said applying means and for permitting movement thereof; means adapted to bear against said surface and movable relatively thereto for guiding said applying means; means resiliently connecting said guiding means to said gas stream applying means whereby said applying means may be moved relatively to said guiding means transversely of said surface; means cooperating with said flexible connecting means for urging said guiding means against said surface; and means for relatively moving said oxidizing gas stream applying means and said body lengthwise of said surface.

3. Apparatus for removing metal from a substantially vertical surface of a body, comprising the combination of means including a nozzle adapted to be disposed adjacent said surface and inclined at an angle thereto for applying at least one oxidizing gas stream thereon; means adapted to contact said vertical surface and the top surface of said body for partly supporting said nozzle and for guiding the same to maintain the tip thereof a substantially constant distance from said vertical surface as it is moved relatively thereto; supporting means; means flexibly connecting said nozzle to said supporting means for partly supporting said nozzle and for permitting vertical and horizontal movement thereof automatically in response to changes in the position of said guiding means, said flexible connecting means being so constructed and arranged that said nozzle will always maintain the same angular position with respect to said vertical surface irrespective of any movement thereof; means cooperating with said flexible connecting means for urging said nozzle and said guiding means toward said vertical surface; and means for relatively moving said nozzle and said body.

4. Apparatus for removing metal from a substantially vertical surface of a body, comprising the combination of means including a nozzle adapted to be disposed adjacent said surface for applying at least one oxidizing gas stream thereon; means resiliently connected to said nozzle and adapted to contact said vertical surface and the top surface of said body for partly supporting said nozzle and for guiding the same to maintain the tip thereof a substantially constant distance from said vertical surface as it is moved

relatively thereto; supporting means; a member mounted on said supporting means and adjustable thereon; means flexibly connecting said nozzle to said member for partly supporting said nozzle and for permitting vertical and horizontal movement thereof; means cooperating with said flexible connecting means for urging said nozzle and said guiding means toward said vertical surface; and means for relatively moving said nozzle and said body.

5. Apparatus according to claim 4, in which said nozzle is disposed at an angle to said vertical surface, and in which said flexible connecting means is so constructed and arranged that 15 said nozzle will always maintain the same angular position with respect to said vertical surface irrespective of any movement thereof, the angular position of said nozzle with respect to said surface being dependent upon the adjusted position 20 of said member mounted on said supporting means; and position indicating means associated with said member and said supporting means.

6. In apparatus for removing metal from an 25 edge surface of a metallic body supported in a substantially horizontal position, the combination of means including a nozzle adapted to be disposed adjacent said edge surface for applying at least one oxidizing gas stream thereon; means adapted to contact said edge surface and 30 the top surface of said body for supporting said nozzle and for guiding the same to maintain the tip thereof a substantially constant distance from said edge surface as said nozzle is moved relatively thereto; and means resiliently connecting said 35 supporting and guiding means to said oxidizing gas stream applying means whereby said applying means may be moved relatively to said supporting and guiding means transversely of said edge surface.

40 7. Apparatus for removing metal from a substantially vertical surface of a body comprising the combination of means including a nozzle adapted to be disposed adjacent to said surface for applying at least one oxidizing gas stream thereon; means connected to said nozzle and adapted to contact said vertical surface and the top surface of said body for partly supporting said nozzle and for guiding the same to maintain the tip thereof a substantially constant distance from said vertical surface as it is moved relatively thereto; supporting means; a member mounted on said supporting means and adjustable thereon; means flexibly connecting said nozzle to said member for partly supporting said nozzle and for permitting vertical and horizontal movement thereof; and means for relatively moving said nozzle and said body.

45 8. Apparatus according to claim 7 in which said nozzle is disposed at an angle to said vertical surface, and in which said flexible connecting means is so constructed and arranged that said nozzle will always maintain the same angular position with respect to said vertical surface irrespective of any movement thereof, and said member 50 mounted on said supporting means is adjustable to have any of a plurality of predetermined angular positions whereby the angular position of said nozzle with respect to said surface is de-

termined by the adjusted position of said member mounted on said supporting means.

9. Apparatus for removing metal from the surface of a body, comprising the combination of 5 nozzle means for applying at least one oxidizing gas stream against said surface; means associated with said nozzle means adapted to engage said surface for guiding said nozzle means to maintain the discharge end thereof a substantially constant distance from said surface as it is moved 10 relatively therewith; supporting means; means for effecting relative movement between said supporting means and said surface; and mechanism movably connecting said nozzle means to said supporting means for providing movement of 15 said nozzle means toward or away from said surface, said mechanism comprising three parallel links having end portions pivotally connected at three separate points to said supporting means and their other end portions pivotally connected 20 at three separate points to said nozzle means.

10. Blowpipe apparatus comprising the combination of nozzle means for applying at least one gas stream against the surface of a metal body; means associated with said nozzle means 25 adapted to engage said surface for guiding said nozzle means to maintain the discharge end thereof a substantially constant distance from said surface as it is moved relatively therewith; supporting means; means for effecting relative 30 movement between said supporting means and said surface; and mechanism movably connecting said nozzle means to said supporting means for providing both vertical and horizontal movement of said nozzle means, said mechanism comprising a plurality of parallel links, each of said 35 links having one end portion universally pivoted to said supporting means and its other end portion universally pivoted to said nozzle means, the pivotal connections being at spaced apart portions of said supporting means and at spaced apart portions of said nozzle means.

40 11. In a blowpipe apparatus for applying gas against a surface of a metal body adjacent an edge corner of said body, nozzle means for applying at least one gas stream against a zone of said surface adjacent and parallel to said edge corner; and mechanism including a roller adapted to simultaneously contact both surfaces of said body forming said edge corner, said mechanism being arranged for supporting said nozzle means in an operative position and for guiding said nozzle means to maintain the tip thereof a substantially constant distance from said adjacent surface of said body and the zone of application of said gas stream at a substantially constant distance from said edge corner during relative movement between said body and said nozzle means along and parallel to said edge corner; said roller having its axis of rotation 45 inclined toward said corner at a relatively small angle to one of said surfaces, said roller having tread surfaces angularly related to each other and to said axis, and an annular recess between said tread surfaces for preventing contact of 50 said roller with said edge corner whereby said nozzle means is guided solely by said surfaces forming the edge corner.
